CAMSHAFT GRINDING MACHINE

Thomas C. Van Degrift and William H. McCoy,
Detroit, Mich.

Application October 26, 1928. Serial No. 315,200

10 Claims. (Cl. 51—101)

This invention relates to pattern controlled machines for forming a given surface contour on cams or other non-round objects.

Objects of the invention are to reduce, in the replica, errors that may unavoidably exist in the pattern; to translate the lift of the pattern into a right line relative movement of tool and work through a pivoted translating mechanism; to minimize friction in a translating mechanism 10 and carrier actuated by the pattern, and otherwise to improve mechanism of this type.

The invention consists of a combination of means for holding a blank workpiece to be shaped and means for holding a shaping tool in operative position with respect to the blank; means for causing relative movement of tool and blank for the purpose of removing or displacing material of the blank, and means for imparting other relative movements of tool and blank for the purpose of producing a precalculated contour. In its application to the specific uses contemplated the blank holding means is rotated with respect to the tool to effect removal or displacement of material and the tool is given an in and out movement with respect to the blank by a rotating pattern of which the object to be produced is a relatively small replica. The pattern is rotated at the same angular speed as the blank and the extent of movement imparted by the pattern 20 to the tool is reduced proportionately to the pre-calculated dimensions of the finished object with respect to those of the pattern.

The invention comprises also various subcombinations and elemental details specifically described hereinafter and illustrated in the accompanying drawings in which:

Fig. 1 is a front elevation of a complete machine;

Fig. 2 is a plan view;

Fig. 3 is an end elevation viewed from the right of Figs. 1 and 2;

Fig. 4 is a horizontal section of a fragment of the machine taken along line 4—4 of Fig. 3;

Fig. 5 is a section on line 5—5 of Fig. 4;

Fig. 6 is an elevation of a rotary tool and its carrier mechanism viewed from the left of Figs. 1 and 2;

Fig. 7 is an elevation of the rotary tool and its carrier mechanism partly in section viewed from the front;

Fig. 8 is a detail view of the main operating lever of the tool carrier, viewed from the front;

Fig. 9 is a detail view in side elevation of the tool carrier supporting bracket and tool guard;

Fig. 10 is a detail in front elevation of the supporting bracket shown in Fig. 9;

Fig. 11 is a section exposing the live center and one end of the work rotating shaft;

Fig. 12 is a detail of a work driving dog to be secured to the work piece, and

Fig. 13 is a sectional detail of a rotating shaping tool, arbor and bearings.

We have illustrated our invention as embodied in a machine for grinding to a precalculated contour the valve operating cams of an internal combustion engine of the four-stroke cycle, poppet-valve type. The machine illustrated and described comprises means for supporting and rotating a work piece or blank to be shaped in contact with a tool, and means for supporting and imparting to the tool movements properly timed and directed to shape the work piece into a finished product of precalculated contour and dimensions.

In Figs. 1, 2 and 3 the work piece or blank supporting base is indicated by numeral 20. A tool supporting base 21 is arranged rearward of the work supporting base. Brackets 22 and 75 for supporting bearings for certain transmission members are connected to the base 21 and a bracket 23 for a similar purpose is connected to the base 20. A pedestal 24 supports a motor 78 for rotating the work piece and moving the tool toward and from the axis of the work by means to be described.

The upper surface of base 20 is provided with the usual ways for supporting a work table 25, which may be adjusted longitudinally by a lead screw or other usual mechanism (not shown) operated by a hand wheel 26 as is common in machine tools. On the table 25 are a head stock 27 and a tail stock 28, both of which may be adjusted longitudinally of the table according to the length of the work piece to be held between them and locked in adjusted position by bolts 29 having T heads engaging an undercut groove 30 in the table as is customary in analogous machines. The tail stock is equipped with the usual adjustable dead center point 31 and the head stock with a live center point 32, between which the work piece 33 may be centered and rotated.

Rotation may be imparted to the centered work piece by a work driving lug 34 associated with the live center. Live center 32 and work driving lug 34 are adapted to be rotated by a shaft 35 journalled in and movable longitudinally with the head stock 27. Shaft 35 is slideable in and through bearings in the bracket 23. Shaft 35 also slides freely through a bevel pinion 36, which is keyed to the shaft and is in mesh with a driving gear on a transmission train to be described presently. Thus the head stock may be adjusted without disturbing the power connections for rotating the work piece.

In order that the work piece 33 may be rotated by the shaft 35 and work driving lug 34, a dog 37 in the form of a short tubular body having in one face a plurality of notches 38 shaped to interlock with the work driving lug 34 is secured to the end of the work piece adjacent the live

center as by a set screw 39. The work piece shown in Fig. 2 is a valve-operating cam shaft for a six cylinder automobile engine. As some of the cams are angularly displaced with respect to others and the relative movements of work piece and tool remain the same, it is necessary to index the work piece after the cam or cams having one angular position have been finished in order to bring it to the proper position for succeeding operations on a cam or cams having different angular position. The notches 38 in the dog 37 are so spaced as to enable the work piece to be held in the proper position with respect to the movements of the tool for any selected cam when the proper notch is interlocked with the driving lug 34, the dog remaining fixed in the same position on the work piece.

The shaping tool illustrated is a grinding or abrasive wheel 40, secured to a rotary toolholder comprising an arbor 50 rotatably mounted in a movable tool carrier 49 operated through a pivoted translating means by a pattern 73. The tool may be rotated by any desired means, such as a belt 41 driven from an overhead pulley and kept taut by suitable belt tightening devices not shown. An adjustable tool carrier and translating means supporting table 42 mounted in suitable ways on the tool base 21 may be adjusted transversely of the work center axis by means of a hand wheel 43 which imparts movement to a transmission device including a lead screw and nut, rack and pinion, or other well known form of machine tool table moving means (not shown).

A bracket or hanger 44 is fixed to and rises from the front part of the table 42, that is, from the part adjacent to the work table 25. Bracket 44 serves as a support, which is adapted to be secured rigidly to the table, for the tool carrier translating means composed of two-limbed or yoke-shaped levers 45 and 46 pivoted to the bracket 44 on journal bolts 47 and 48, respectively (Fig. 7). The tool carrier consists of parallel links 49, pivoted to levers 45 and 46, in which the arbor 50 carrying the abrasive wheel 40 and belt pulley 51 rotates. Bracket 44 also serves as a protecting housing enclosing the major portion of the circumference of the abrading wheel 40 by means of its curved back wall and two parallel side webs 52 projecting from the concave side of the back wall and merging into the forward overhanging portion 54. In Figs. 1, 6 and 7 an additional shield member 53 is shown attached to the upper forward projection 54 of the bracket.

Yoke shaped lever 45, constituting the forward and idle oscillatory member of the tool carrier translating linkage, comprises limbs 57 connected together by a cross member 62 having a stiffening rib 63, and is pivoted or fulcrumed at its lower end on the journal bolts 47 which pass through bearing ears 55 and are threaded, respectively, in sockets drilled into the opposite ends of an enlargement 56 formed on the lower forward portion of bracket 44 in the construction shown. The operating or active lever 46 is composed of two parallel limbs 64 connected near the point of application of the power,—at its lower end as shown,—by a transverse member 65 (Fig. 4) and near the fulcrum end—shown as at its upper end—by a shield-like strengthening member 66 curved rearward over the rear of bracket 44. The fulcrum bearings of idle lever 45 and active lever 46 are preferably ball bearings, as shown in Fig. 7 at the fulcrum of lever 46, wherein 70 indicates the bearing balls. A bearing ear 68 on the fulcrum

end of each limb 64 is perforated to receive the ball bearing and permit the passage of the journal bolts 48 which are screwed into the ends of enlargement 69 on the bracket 44. At each fulcrum bearing of active lever 46 and idle lever 45 a cover such as cap 71 having a grease hole 72, with cup or cover therefor, protects the bearing and provides for lubrication. Depending from the lower transverse member 65 of the lever 46 is an extension 67 slotted to receive a bearing roller 66 pivoted thereto, in contact with which is a member for imparting movement to said lever to be presently described.

The parallel links 49 referred to as constituting the tool carrier supporting the tool arbor 50 have their ends pivoted, preferably by ball bearings, to the levers 46 and 45 as best shown in Figs. 6 and 7. One of these pivotal bearings is illustrated in detail in Fig. 7 wherein 60 indicates a bearing pin fixed to spaced cheeks of one limb of the idle lever 45, and 59 bearing balls interposed between the pin and the wall of the bearing cavity in one end of the tool supporting link 49 disposed between the cheeks. The bearing pin 60 is shown as tubular with a bore flaring at each end and longitudinal kerfs to permit of expansion of the ends, which may be accomplished by means of an expansion bolt 61 having a conoidal head at one end and a conoidal nut at the other end. The front end and bearing of each tool supporting link 49 is confined between the cheeks in the upper end of each arm of idle lever 45 while the rear end and bearing of each of said links 49 is confined in a slot or cavity 72 forming spaced cheeks in each limb 64 of the active lever 46. The axis of the pivot connections of the links 49 with idle lever 45 is the same distance from the fulcrum axis of said lever 45, as is the axis of the pivot connection of links 49 to active lever 46 from the fulcrum axis of said lever. When the active lever 46 is in the mid-throw position, as indicated in the drawings, the plane that includes the fulcrum of lever 46 and the axis of the pivotal connection of links 49 thereto is parallel to the plane that includes the fulcrum of lever 45 and the axis of its pivotal connection to links 49; also, at this time, the plane including the axes of the pivotal connections of the links 49 to the lever 45 and lever 46 is at right angles to the former planes and parallel with the plane of adjustment of the tool supporting table 42. The tool arbor 50 is journalled in the links 49 about an axis midway between the pivotal connections of the links 49 to the lever 45 and lever 46 and preferably in the same plane. Within the amplitude of movement of the tool axis in practical operation (not greater than one quarter inch in the machine illustrated) that axis moves in a plane parallel with the plane of adjustment of both tool and work supporting tables. The movement of any point on the axis is practically a right line movement, notwithstanding the rocking movement or change in angular position of links 49 due to the opposite directions in which the levers 45 and 46 extend from their fulcrum points.

Fig. 13 shows the details of the tool holder comprising an arbor and associated parts and the bearings of said arbor in tool carrier links 49, which are so constructed that the axis of the tool may be maintained with accuracy in the same relative position with respect to the links 49 at all times. The mid portion 100 of arbor 50 is tapered to receive hub 101 of belt pulley 51. Adjacent the small end of tapered portion 100 the arbor is threaded to receive a nut 102 which locks the pulley on the arbor. Abrading or grinding

wheel 40 is sleeved over the hub 101. It is held between a flange 103 on the pulley and a clamping ring 104. A nut 105 screwed on a threaded part of the hub 101 clamps the wheel 40 against the flange 103. Suitable gaskets are disposed between the grinding wheel and the clamping means. The end journal portions 106 of arbor 50 are oppositely tapered and are of course smaller in diameter than tapered portion 100 so that the pulley and grinding wheel may be assembled. Internally tapered bearing bushings 107 of bronze or other approved bearing material are tightly fitted in openings formed in links 49 to receive the tapered journals of the arbor. Links 49 are provided with threaded bosses 108 coaxial with the bushing openings for receiving threaded caps 109 and 110. Caps 109 bear against bushings 107 and serve to adjust them on the tapered journals to secure accurate adjustment and take up wear. Each bearing bushing overhangs or projects somewhat beyond the extremity of arbor 50 for this purpose. Within the cup like cavity formed by the extremity of the arbor and the overhanging portion of each bushing thrust disks 111 of some good bearing material are seated; thrust screws 112 are threaded through openings in caps 109, into contact with the disks and thus maintain the endwise adjustment of the arbor 50. The thrust screws 112 may be locked against movement when adjusted by lock nuts 113.

Translating means between the pattern and tool carrier for moving the tool toward and away from the axis of the work to give to the work a pre-calculated contour are shown in Figs. 3 and 4. In these views numeral 73 indicates the pattern, as illustrated a master cam, which is an enlarged replica of a cam to be shaped by the abrading tool 40. The pattern in the exemplary apparatus illustrated is secured to a shaft 74 journaled in bearing bracket 75, and in bearing lugs 76 and 77 on bracket 22 rigid with the tool base of the apparatus. Shaft 74 is rotated by said electric motor 78 mounted on pedestal 24, a worm 80 rotating with the armature shaft 79 and driving a worm wheel 81 on shaft 74. Shaft 74 transmits rotation to work rotating shaft 35 by means of a transverse shaft 82 provided with bevel gears 83 and 84 on its respective ends which mesh respectively with a bevel gear 85 on shaft 74 and bevel gear 36 secured slidably to shaft 35 as before stated. The gearing is designed to give shafts 74 and 35 the same angular speeds.

Referring to Figs. 3, 4 and 5, numeral 86 indicates an element moving in a straight line—as illustrated a slide reciprocating in a guide way formed on top of guide standard 87 inside of base 21 which forms a housing for it and other associated moving parts. At its forward end slide 86 has a lever wear member 89 which bears against the roller 66' on the projection 67 at the power end of lever 46. Detachably attached to the opposite end of a slide 86 is a yoke 90 carrying at its rear a pattern wear plate 91 which bears against the pattern 73 and is arranged in line with wear member 89. Tension spring 92 has one end attached to lever 46 and its other end attached to slide 86, with the result that the wear member 89 is always maintained elastically in contact with the roller 66' on the lever. Tension spring 93 has one end attached to the base 21 at 94 and its other end attached to the yoke member 90 and so tends to maintain the wear member 91 elastically against the pattern. The bearing surfaces of wear members 89 and 91 are curved in the planes of movement of lever 46

and the eccentric portion or lift of the pattern, respectively; member 91 is preferably removable and replaceable. By this construction the tool is allowed to approach the work and is moved away from it by controlled elastic forces; all cutting pressure is produced by an elastic force. To guide the yoke 90 a guiding extension 95 slides in a way formed in a rigid bracket 96.

Assuming that the lines radiating from the axis of rotation of the pattern cam illustrated to its surface having a ratio of 5 with respect to the corresponding lines radiating from the center of the finished cam to be shaped by the tool, the distance from the fulcrum of lever 46 to the point of application of the power,—the axis of the bearing roller 66'—is five times the distance from the fulcrum to the point of application of said lever to the work which is the pivotal axis of the connection of link 49 to lever 46. With a leverage of 5:1 the curvature of the operating face of wear member 89 necessary to compensate for the angular movement of links 49 around the center of the tool axis, which moves in a straight line, may be calculated. The curvature of the member 89 as the roller 66' moves over it, due to the angular movement of lever 46, therefore permits of a decreased amplitude of movement of the point of connection of link 49 to lever 46 sufficient to compensate for the decreased relative movement of the tool axis due to the slight rocking movement of the link 49 on which the tool is carried.

When the shaping tool is a rotary tool, such as abrading wheel 40 shown in the drawings, the wear member 91 on yoke 90 is curved so that the high point or extremity of the lift of the pattern will first contact with a low point in the surface of wear member and afterward with the high point thereof. In the mechanism shown the surface of wear member 91 on yoke 90 is curved in a plane at right angles to the axis of pattern cam 73, that is, in the plane that defines the contour of the lift. Where the leverage is in a ratio of 5 to 1 as described the radius of curvature of wear member 91 is five times the radius of abrading wheel 40. By making the wear member 91 removable it may be removed and replaced by one of a different curvature in case a larger or smaller abrading wheel is used or after wear of the abrading wheel. Thus the relation of the abrading wheel to the cam being shaped is substantially identical with the relation of the operating wear member 91 to the pattern cam.

The operation of the form of apparatus illustrated is as follows: The work piece or blank,—shown in the drawings as a roughed cam shaft for a six cylinder internal combustion engine,—is inserted between the centers of the head and tail stock; the blank is then indexed to bring the blank cam to be ground into the same angular position as the pattern or master cam. The tool and work tables are adjusted to correct working position for the particular piece to be shaped. The abrading tool is caused to rotate on its own axis, and the pattern cam and work rotating shaft are caused to rotate at identical angular speeds by the prime mover therefor and the transmitting mechanism as explained hereinbefore. Spring 92 holds the roller 66' on the lower end of the lever 46 in contact with the front end of slide 86 and spring 93 holds the curved wear member 91 in contact with the pattern cam 73, thus causing the linkage which supports the abrading wheel 40 to move about the several pivotal points during rotation of the pattern in such

manner as to impart to the abrading wheel a right line movement exactly proportionate in extent to the right line movement of the operating slide 86 imparted by the pattern cam, as predetermined by the proportions of the cam being ground to those of the pattern cam. The pressure of tool on work is an elastic pressure. A large model of the cam to be ground can be produced with a high degree of accuracy and this can be used as a pattern to operate or control the relative movements of tool and work. By reason of the proportions of the linkage by which the tool carrier is operated by the pattern cam it is possible to reduce in the finished replica the errors that may be present, in spite of the greatest care, in the pattern or master cam. A right line movement of the tool is obtainable through a carrier which is mounted on pivotal bearings instead of sliding on guide ways whereby frictional resistance to the movements of the tool to and from the work is minimized and a more delicate and precise functioning secured.

Although we have in accordance with the statutes described the best embodiment of our invention now known to us, we do not intend the patent to be limited to the specific embodiment described as the principles involved are applicable to different forms of mechanism.

We claim:

1. In pattern controlled apparatus of the class described, the combination of a rotary tool and holder therefor, a work holder, a pattern, means for rotating the work holder and pattern at equal angular speeds, a translating means operated by the pattern comprising a lever mechanism, a carrier pivotally supported on the lever mechanism, a bearing on the carrier for the tool holder, and means for causing the axis of the tool holder to approach and recede from the work holder center in right line movements.

2. A combination as defined in claim 1, in which the translating means operated by the pattern comprises an actuating lever, to which said carrier is pivoted at a point nearer the fulcrum than the point of application of the force, due to the rotation of the pattern, to said lever.

3. A combination as defined in claim 1, in which the translating means comprises a pair of levers arranged in tandem and extending in opposite directions from their fulcrum points, said carrier being pivoted to each of said levers on axes equidistant from the fulcrum points of the levers, said tool holder being supported on said carrier midway between the pivotal connections of the carrier to the levers.

4. A combination as defined in claim 1 in which the translating means comprises a pair of levers arranged in tandem and extending in opposite directions from their fulcrum points, said carrier being pivoted to each lever at points equidistant from the fulcrum points of the levers, a bearing for supporting the tool holder on the carrier at the point of right line movement in the carrier, said pattern being arranged to transmit movement to one of said levers at a point on said lever that is a greater distance from its fulcrum than the connection of the carrier thereto.

5. In pattern controlled forming apparatus of the class described, a rotatable work holder, a rotatable tool holder, mechanism for moving the tool holder to and from the axis of the work

holder, comprising pivoted lever mechanism, a carrier supported by and pivoted to said lever mechanism, a bearing for said tool holder on said carrier, means for causing the carrier to move the tool holder axis in a substantially straight line, a pattern arranged to operate the pivoted lever mechanism, means to rotate the pattern and work holder at equal angular speeds, and means interposed between the pattern and the lever mechanism constructed and arranged to compensate for the angular movement of the carrier and cause the axis of the tool holder to travel a distance proportionate to the throw of the pattern with respect to the desired throw of the work piece.

6. A combination as defined in claim 5 in which the means interposed between the pattern and the lever mechanism comprises an element moving in a straight line having one end convexly curved in the plane of movement of the lever mechanism and bearing against a roller on said lever mechanism.

7. In pattern controlled mechanism of the class described the combination of a rotary work holder, a rotary tool holder, a carrier therefor, a pattern, means for rotating the pattern and work holder at equal angular speeds, a translating mechanism between said pattern and tool carrier comprising levers arranged in tandem and extending in opposite directions from their fulcrum points, said tool carrier being pivoted to both of said levers at substantially equal distances from their fulcrum points, said tool holder being supported with its axis substantially midway between said levers, an element guided in a straight line movement interposed between said pattern and one of said levers, the end of said element bearing upon the lever at a point further from its fulcrum than the point of connection thereto of the tool carrier and having a curvature in a plane parallel with the plane of the lift of said pattern.

8. In pattern controlled forming mechanism of the class described, a tool holder, a work holder, a pattern, and means for rotating said pattern and one of said holders at equal speeds, a translating means between the pattern and the other holder comprising a pivoted lever, a carrier for said other holder pivoted to the lever, and means to guide in a straight line that part of the carrier to which the holder is attached, a slidale member controlled by the pattern, said slidale member having one end bearing against the lever and having said end contoured to compensate for the tilting of the carrier and a spring arranged to maintain contact between the lever and the end of the slidale member bearing against the lever.

9. A combination defined in claim 8 with the addition of a spring exerting its elasticity to maintain the slidale member in contact with the pattern.

10. The combination defined in claim 8 in which the tool holder is rotatable and is mounted on the carrier pivoted to the lever, and the slidale member is provided with a removable device having a surface arranged to engage the pattern, said surface being of a curvature, in a plane parallel to the plane of rotation of the pattern, the radius of which has the same proportion to the radii of the pattern that the radius of the cutter bears to the radii of the work piece desired.

WILLIAM H. McCOY.

THOMAS C. VAN DEGRIFT.
